UNITED STATES PATENT OFFICE.

JOACHIM GIARDINO, OF WEST NEW YORK, NEW JERSEY.

HEDDLE-FRAME FOR LOOMS.

1,082,317.

Specification of Letters Patent.

Patented Dec. 23, 1913.

Application filed December 16, 1912. Serial No. 736,902.

To all whom it may concern:

Be it known that I, JOACHIM GIARDINO, a citizen of Italy, and residing at West New York, in the county of Hudson and State of New Jersey, have invented certain new and useful Improvements in Heddle-Frames for Looms, of which the following is a specification, such as will enable those skilled in the art to which it appertains to make and use the same.

The object of this invention is to provide an improved heddle frame consisting of separate detachable parts constructed in such manner that the heddles may be quickly and easily assembled therein and adjusted into any desired position, and the separate parts of the frame connected, and with this and other objects in view the invention consists of a heddle frame constructed as hereinafter described and claimed.

The invention is fully disclosed in the following specification of which the accompanying drawing forms a part, in which the separate parts of my invention are designated by suitable reference characters in each of the views, and in which—

Figure 1 is a side view of a heddle frame constructed according to my invention with part of the construction broken away, and Fig. 2 a section on the line 2—2 of Fig. 1; Fig. 3 a section on the line 3—3 of Fig. 1; Figs. 4, 5 and 6 transverse sectional views showing modified forms of the top and bottom parts of the frame, and; Fig. 7 a detail view of a suspending clamp which I employ.

In the practice of my invention, I provide a heddle frame having horizontal and parallel top and bottom members *a* and *b* and parallel end members *c*. The top and bottom members *a* and *b* consist of flat hollow tubes the outer opposite faces of which are convex in cross section and the inner or adjacent faces of which are provided with longitudinal side flanges *a*² and *b*² forming longitudinal slots *a*³ and *b*³, through which the heddles *d* are free to move longitudinally of the frame. Within the top and bottom members *a* and *b* of the frame are placed bars *e* which may be flat in cross section, as shown in Figs. 1 to 3 inclusive, or round as shown at *e*² in Fig. 4, and the heddles *d* may be either flat, as shown in Figs. 1 to 3 inclusive or they may consist of wires *d*², as shown in Fig. 4, and when flat heddles *d* are used the ends thereof are provided with

oblong slots or openings *d*³ through which the flat bars *e* are passed, and when the wire heddles *d*² are used they are provided with rings or eyes *d*⁴.

The end members *c* of the frame consist of flat metal strips folded around the end portions of the top and bottom members *a* and *b*, as shown at *c*², the ends of said strips being secured to the body portion thereof by bolts or screws *f* having nuts *f*², and placed in the ends of the top and bottom members *a* and *b* are blocks *g* which fill said top and bottom members transversely and are provided with shanks *g*² which pass inwardly through the slots *a*³ and *b*³ and are secured by the bolts or screws *f* which are passed therethrough, as clearly shown.

The blocks *g* which close the ends of the top and bottom members *a* and *b* of the frame are provided on their inner faces with recesses *g*³ to receive the ends of the bars *e* and *e*², and mounted on said bars, when in use, are supplemental block or link-shaped bearing devices *h* which are approximately of the same form in cross section as the top and bottom members *a* and *b* of the frame, and which are freely movable on said bars within said top and bottom members and may be adjusted into any desired position, and these blocks or links are intended to strengthen and support the bars *e* or *e*², and to hold them in proper position and form, it being understood that, in practice, these bars are necessarily made smaller and light.

Mounted on the top member *a* of the frame is a suspending clamp *i* which is yoke-shaped in form the bottom thereof being open and provided with inwardly directed side flanges *i*² forming hooks adapted to engage the top member *a* of the frame, and the top portion of which is thickened, as shown at *i*³, and provided with a screw hook *i*⁴ which is passed downwardly therethrough, and the top of the tubular frame bar *a* is provided with an aperture *i*⁵ to receive said screw. It will be understood that a number of these suspending clamps *i* may be employed, if desired, and they may be adjusted into any desired position on the top member *a* of the frame. The top, bottom and end portions of the frame are also connected by screws *j*, and with this construction the parts of the frame may be disconnected and the heddles taken out whenever desired by simply removing these screws and the screws or bolts *f*, and said

parts may be as quickly and easily assembled whenever necessary.

The slot in the bottom of the top member *a* of the frame and in the top of the bottom member *b* of the frame, or the walls of said slots, may be reinforced, as shown at *a*⁴ and *b*⁴ in Figs. 5 and 6, and it will be understood that the original dimensions of the frame are the same as of other devices of 10 this class, and any number of the heddles *d* or *d*² may be employed, and changes in and modifications of the construction herein described may be made, within the scope of the appended claims, without departing 15 from the spirit of my invention or sacrificing its advantages.

Having fully described my invention what I claim as new and desire to secure by Letters Patent, is:—

- 20 1. A heddle frame the top and bottom members of which are composed of hollow flattened tubes the inner faces of which are provided with central longitudinal slots through which the heddles pass and which 25 form inwardly directed flanges, said tubes being also provided with central longitudinal bars which pass through the ends of the heddles and with bearing devices freely movable therein longitudinally thereof and which rest on said flanges and through 30 which said bars are loosely passed.
- 35 2. A heddle frame the top and bottom members of which are composed of hollow flattened tubes the inner faces of which are provided with central longitudinal slots through which the heddles pass and which 35 form inwardly directed flanges, said tubes

being also provided with central longitudinal bars which pass through the ends of the heddles and with bearing devices freely 40 movable therein longitudinally thereof and which rest on said flanges and through which said bars are loosely passed, the ends of said tubes being also closed by blocks which fit therein and in which the ends of 45 said bars are supported.

3. A heddle frame the top and bottom members of which are composed of hollow flattened tubes the inner faces of which are provided with central longitudinal slots 50 through which the heddles pass and which form inwardly directed flanges, said tubes being also provided with central longitudinal bars which pass through the ends of the heddles and with bearing devices freely 55 movable therein longitudinally thereof and which rest on said flanges and through which said bars are loosely passed, the ends of said tubes being also closed by blocks which fit therein and in which the ends of 60 said bars are supported, and the sides of said frame being composed of metal strips which are folded around the ends of said tubes and detachably secured thereto and to 65 said blocks.

In testimony that I claim the foregoing as my invention I have signed my name in presence of the subscribing witnesses this 14th day of December 1912.

JOACHIM GIARDINO.
